UNITED STATES PATENT OFFICE.

HENRY B. TURNER, OF HUNTINGTON, WEST VIRGINIA.

SHADE- XT. E.

No. 819,957.

Specification of Letters Patent.

Patented May 8, 1906.

Application filed March 5, 1906. Serial No. 304,299.

To all whom it may concern:

Be it known that I, HENRY B. TURNER, a citizen of the United States of America, and a resident of Huntington, county of Cabell, State of West Virginia, have invented certain new and useful Improvements in Shade-Fixtures, of which the following is a full and clear specification; reference being had to the accompanying drawings, in which—

10 Figure 1 is a perspective view showing my fixture as it appears when applied to a window, the connecting-chain being shortened for the purposes of better illustration; and Fig. 2, a horizontal sectional view of one of the brackets.

15 The object of this invention is to provide simple devices which may be attached to a window-frame without marring the same and which are adjustable to various sizes of 20 window-frames, as more fully hereinafter set forth.

25 To the accomplishment of this object and such others as may hereinafter appear the invention consists of the parts and combination of parts hereinafter fully described, and particularly pointed out in the appended claims, reference being had to the accompanying drawings, forming a part of this specification, in which the same reference characters designate like parts throughout the several views.

30 This device consists of a pair of main brackets adapted to be connected by a chain F, which is drawn taut across the upper part 35 of the window-frame, each of these brackets being constructed as follows: A main plate A is provided with a pair of horizontal parallel slots a, in which slide the headed rivets or pins d² of a vertical shade-bracket D, provided with the usual shade-supporting ear d, one of these ears being provided with the usual open slot d' and the other being provided with the usual closed hole d³ for the reception of the pintles of the shade-roller. 40 Each plate A is provided at its outer end with a vertical flange a', which carries a pair of headed rivets or pins a², which extend through a pair of guide-slots b, formed in a bracket-plate B, extending forwardly from the plate 45 A, as well as rearwardly therefrom, its backward-extending part being provided with an inwardly-turned toothed flange p, extending along its vertical edge. On each of the plates B is mounted a sliding plate C, provided at 50 its outer end with a depression or notch c for the reception of the curtain-pole. This plate

55 C is rendered slidable by means of the headed rivet b³, carried by the plate B and working in a slot c in said plate C, and by a set-screw c², carried by the plate C and working in a horizontal slot in plate B, by which arrangement the plate C may be adjusted to and from the window-frame and locked in its adjusted position.

60 The chain F detachably engages at its opposite ends the hooks e, formed on the respective inner ends of the threaded rods E, each of whose outer ends extends through flange a' and plate B, the plate B being provided with a horizontal slot b' where the rod 70 passes through it. Each rod is guided by a tubular bracket a³ on the front face of plate A, and each rod also passes through the adjacent shade-bracket, which is adjustably clamped to the rod by means of a pair of nuts e'. 75

It will be observed that to apply the device to a window-frame the plates A are placed against the face of the window-frame, at opposite sides thereof, with the serrated rear edges of the plates B bearing against the 80 respective vertical edges of the frame. Then by screwing up the thumb-nuts n on the outer projecting ends of the rods E the two brackets are drawn toward each other, and the teeth p are forced into the woodwork of the 85 frame, a portion of the frame being shown at W in Fig. 2. In this way the brackets are clamped to the frame without the use of extraneous fastening devices and in such manner that the frame will not be marred. It will 90 be observed also that the device has a sufficiently wide range of adjustment to permit it to be applied to frames of various widths. It will be observed, further, that the shade-brackets may be adjusted to accommodate 95 shades of different widths and when so adjusted may be rigidly but movably locked in position. It will be observed also that the tightening of the thumb-nuts on the threaded rods not only draws the two brackets together to embed the teeth p in the frame, but also clamps the two main plates of each bracket together. 100

Having thus fully described my invention, what I claim, and desire to secure by Letters 105 Patent, is—

1. In combination, a pair of main brackets consisting each of two plates attached together at a right angle with each other, pole-supports on the forwardly-projecting plates 110 and frame-engaging means on the rear edge of said forwardly-projecting plates, a shade-

bracket slidably mounted on each of the base-plates, a threaded rod mounted in each of the main brackets and extending inwardly and engaging one of the shade-brackets, and 5 a chain connecting the inner ends of said threaded rods.

2. In combination, a pair of main brackets each consisting of a base-plate and a forwardly-projecting pole-supporting plate, the 10 two plates being adjustably connected together and the rear edge of the pole-supporting plate being provided with window-frame-engaging means, a shade-bracket slidably mounted on each of the base-plates, a thread-

ed rod mounted in each of the main brackets 15 and provided with an adjusting-nut on its outer end, nuts on each threaded rod adapted to engage the adjacent shade-bracket and hold it in place, and a chain connecting the inner ends of the threaded rods. 20

In testimony whereof I hereunto affix my signature, in the presence of two witnesses, this 2d day of March, 1906.

HENRY B. TURNER.
